UNITED STATES PATENT OFFICE.

STEPHEN M. HAMBLIN, OF CENTRAL FALLS, RHODE ISLAND, ASSIGNOR TO
HARRY W. SMITH, OF WORCESTER, MASSACHUSETTS.

ELECTRICAL WEFT-INDICATOR MECHANISM FOR LOOMS.

SPECIFICATION forming part of Letters Patent No. 694,961, dated March 11, 1902.

Application filed October 12, 1899. Serial No. 733,358. (No model.)

To all whom it may concern:

Be it known that I, STEPHEN M. HAMBLIN, a citizen of the United States, residing at 696 Broad street, Central Falls, in the county of Providence, State of Rhode Island, have invented a certain new and useful Improvement in Electrical Weft-Indicator Mechanisms for Looms, of which the following is a specification, reference being had therein to the accompanying drawings.

The invention comprises novel devices by means of which when the supply of weft or filling contained in the shuttle at work on the lay of a loom becomes exhausted to a predetermined extent an electric circuit is closed.

The preferred embodiments of the essential features of the invention are illustrated in the accompanying drawings, in which—

Figure 1 shows in front elevation part of the lay of a loom with a shuttle contained in the shuttle-box, portions being broken out in order to render clear details which otherwise would be concealed. Fig. 2 is a view in cross-section on line 2-2, Fig. 1, on an enlarged scale and looking in the direction that is indicated by the arrows near the ends of such line. Fig. 3 is a front elevation, on an enlarged scale, of part of the loom-shuttle that is represented in Fig. 1. Fig. 4 is a sectional plan thereof. Fig. 5 is a partial plan of a loom-shuttle, showing the manner of practicing my invention in case of the use of weft or filling in cop form.

Having reference more especially to Figs. 1 and 2, 1 designates one of the swords of the lay of a loom; 2, the lay-beam; 3, the back of a shuttle-box; 31, the metal bottom of the said shuttle-box; 4, the mouth portion of the shuttle-box, and 5 a shuttle-binder, only portions of the binder being represented in Fig. 1. 6 is the body of a loom-shuttle, it being shown in position in the shuttle-box in these figures. Within the shuttle-body 6 I place two contacts or feelers, as 7 7. (See also Figs. 3, 4, and 5.) These are arranged to make contact at different points with the load of weft or filling that is placed on the filling-carrier within the shuttle-body and are borne by spring-pressure against such load, so as to cause them to follow inwardly toward the said filling-carrier as the diameter of the portion of

such load which they touch decreases in consequence of the unwinding of the yarn. Herein the said spring-pressure is secured by forming the feelers 7 7 of strips of spring metal 55 having one end of each fixed to the shuttle-body, while the other is free and is bent toward the filling-carrier. The positions of the free ends of the feelers are such that when the filling-carrier, with its load of weft or 60 filling, is depressed into position within the cavity of the shuttle-body the feelers are pressed upon by the surface of the yarn-load, and thereby put under sufficient stress to bring into play their spring force. A convenient position of the free ends of the feelers is illustrated in the drawings, in which latter the said free ends are shown located on opposite sides horizontally of the filling-carrier and arranged to make contact with the yarn-load at such sides. With this arrangement 65 the feelers are pressed outwardly away from each other as the filling-carrier with its yarn-load is forced down between them.

The filling-carrier in Figs. 1, 3, and 4 is in 70 the form of a bobbin 8. The said bobbin is shown applied to a pivoted spindle 9, as usual in loom-shuttles. When bobbins are not employed and weft or filling in cop form is applied to the spindle 9, as is in practice the 75 case with the loom-shuttle of Fig. 5, the spindle itself is to be regarded as the filling-carrier for the purpose of the present invention. So long as the feelers rest in contact with 80 yarn forming part of the yarn-load on the filling-carrier the free ends thereof remain electrically insulated from each other by such yarn. They remain thus insulated from each other until the gradual unwinding of the yarn bares the portion of the filling-carrier which 85 is immediately adjacent the feelers and permits the free extremities of the latter to make contact therewith. In order that when this contact occurs the said extremities of the two feelers may be in electrical communication with each other, the filling-carrier is 90 formed of or provided with suitable conducting material. In the present instances, in 95 Figs. 1, 3, and 4, the head of the bobbin is furnished with a metal band or ring surrounding the same, as at 10. In Fig. 5 the spindle is shown as having a brass or copper 100

ring 100 placed thereon, although this may be dispensed with and the feelers may be permitted to make contact with the spindle directly.

5 The feelers 77 are shown as having the butt-ends thereof set in cuts or kerfs 1111 (see dotted lines, Fig. 3) in the wood of the shuttle-body at opposite sides thereof. Pins 1212 are driven through the said ends for the purpose of securing the feelers in place.

In order that the feelers may be placed in electrical communication with electric terminals or contact-pieces outside of the shuttle-body, I provide in connection with each feeler

15 a movable contact-piece 13. These are made in the form of rings or washers of suitable metal. They are located in narrow cavities 1414 in the shuttle-body immediately alongside the feelers and make contact by their

20 sides with the sides of the latter. They are held in place by pins or pivots 1515, the latter passing through the feelers also and assisting to secure the feelers in place. The central holes 16 through the said rings or

25 washers are somewhat larger in diameter than the pins or pivots 1515, and in consequence the rings or washers are free not only to turn around the latter, but to move vertically with relation to the shuttle-body. The said movable contact-pieces 1313 tend normally to drop or gravitate into the position which is

30 represented in Fig. 2, so as to project slightly from the shuttle-body. During the flight of the shuttle the said movable contact-pieces 35 roll along the surface of the shuttle-race, passing lightly over the warp-threads without marking or otherwise injuring the latter. The fixed contact-pieces or terminals with which the movable contact-pieces 1313, carried by the shuttle, coact are designated 17

40 17. They are located in the shuttle-box at the places where the movable contact-pieces stand while the shuttle is at rest, being set in holes in the bottom 31 of the shuttle-box

45 at opposite sides of the usual slot for the picker and being suitably insulated from the metal portions of the shuttle-box. Preferably the upper surfaces of the said fixed contact-pieces or terminals are lowered a little

50 with reference to the upper surface of the bottom of the shuttle-box, and they are elongated in the direction of the length of the shuttle-box in order to compensate for differences in the position of the shuttle after being

55 stopped at the ends of successive flights. As the shuttle comes to rest in the shuttle-box at the end of its flight the gravitating contact-pieces 1313 drop into contact with the upper faces of the fixed contact-pieces or terminals.

1819 are wires connecting with the fixed contact-pieces or terminals 1717 and also with the battery or other source of electrical power, (indicated at 20.) An electromagnet (indicated at 21) is also included in the circuit, it constituting a means of bringing into action

60 stopping or other devices which are intended

to be brought into play whenever the supply of weft or filling provided on the filling-carrier in the working shuttle on the lay becomes 70 exhausted or depleted to the predetermined extent. Every time that the shuttle comes to rest in the shuttle-box the gravitating movable contact-pieces 1313 make contact with the upper surface of the fixed contact-pieces 75 or terminals 1717 on the lay. So long, however, as electrical communication between the spring-feelers 77 is broken on account of the presence of yarn on the filling-carrier under the extremities of such pressers the electric circuit is kept open and the electromagnet 21 remains inert. When the exhaustion or depletion of the yarn-load bares the filling-carrier and permits the spring-pressers to make contact therewith, the circuit is closed 80 or completed and the electromagnet is energized, whereby the stopping or other devices which are operated therefrom are brought into action.

I claim as my invention—

1. In combination, a shuttle-body, electrical contacts or feelers within the same, means of electrically bridging the interval between such contacts or feelers on exhaustion or depletion of the yarn-load in the shuttle to a 95 predetermined extent, and gravitating movable contact-pieces in electrical communication with the said electrical contacts or feelers.

2. In combination, a shuttle-body, electrical contacts or feelers within the same, means of electrically bridging the interval between such contacts or feelers on exhaustion or depletion of the yarn-load in the shuttle to a 100 predetermined extent, gravitating movable contact-pieces in electrical communication with the said electrical contacts or feelers, the lay, contact-pieces or terminals applied thereto, coacting with the said movable contact-pieces, and an electric circuit including 105 such contact-pieces on the lay.

3. In combination, a shuttle-body, a filling-carrier composed wholly or in part of conducting material, a pair of electrical spring-feelers carried by the said shuttle-body, 115 adapted to bear against different portions of the yarn-load on said filling-carrier, and placed in electrical communication with each other on making contact with portions of said filling-carrier bared by the unwinding of the yarn, and gravitating movable contact-pieces in electrical communication with the said electrical feelers.

4. In combination, a shuttle-body, a filling-carrier composed wholly or in part of conducting material, a pair of electrical spring-feelers carried by the said shuttle-body, 125 adapted to bear against different portions of the yarn-load on said filling-carrier, and placed in electrical communication with each other on making contact with portions of said filling-carrier bared by the unwinding of the yarn, gravitating movable contact-pieces in electrical communication with the said elec- 130

- trical feelers, the lay, contact-pieces or terminals applied thereto coating with the said movable contact-pieces, and an electric circuit including such contact-pieces on the lay.
- 5 5. In combination, a shuttle-body, electrical contacts or feelers within the same, means of electrically bridging the interval between such contacts or feelers on exhaustion or depletion of the yarn-load in the shuttle to a predetermined extent, and gravitating rotating rings or washers in electrical communication with the said electrical contacts or feelers and constituting movable contact-pieces.
- 10 6. In combination, a shuttle-body, electrical contacts or feelers within the same, means of electrically bridging the intervals between such contacts or feelers on exhaustion or depletion of the yarn-load in the shuttle to a predetermined extent, gravitating rotating rings or washers in electrical communication with the said electrical contacts or feelers and constituting movable contact-pieces, the lay, contact-pieces or terminals applied thereto, 25 coating with the said movable contact-pieces, and an electric circuit including such contact-pieces on the lay.
7. In combination, a shuttle-body, electrical contacts or feelers within the same, means of 30 electrically bridging the interval between such contacts or feelers on exhaustion or depletion of the yarn-load in the shuttle to a predetermined extent, and movable contact-pieces in electrical communication with the 35 said electrical contacts or feelers and tending with yielding force to project into their normal positions.
8. In combination, the lay, contact-pieces or terminals applied thereto, an electric circuit including such contact-pieces or terminals, a shuttle - body, electrical contacts or feelers within the same, means of electrically

bridging the interval between such contacts or feelers on exhaustion or depletion of the yarn-load in the shuttle to a predetermined extent, and movable contact-pieces carried by the shuttle-body, in electrical communication with the said electrical contacts or feelers, and tending with yielding force to project normally into position to engage with the said contact-pieces or terminals on the lay.

9. In combination, a shuttle-body, a filling-carrier composed wholly or in part of conducting material, a pair of spring-feelers carried by the shuttle-body, adapted to bear against different portions of the yarn-load on said filling-carrier, and placed in electrical communication with each other on coming in contact with portions of said filling-carrier bared by the unwinding of the yarn, and the 50 gravitating rings or washers in electrical communication with the said spring-feelers and constituting movable contact-pieces.

10. In combination, a shuttle-body, a filling-carrier, composed wholly or in part of 65 conducting material, a pair of spring-feelers carried by the shuttle-body, adapted to bear against different portions of the yarn-load on said filling-carrier and placed in electrical communication with each other on coming in 70 contact with portions of said filling-carrier bared by the unwinding of the yarn, the gravitating rings or washers in electrical communication with the said spring-feelers and constituting movable contact-pieces, the lay, 75 contact-pieces or terminals applied thereto, and an electric circuit including the latter contact-pieces or terminals.

In testimony whereof I affix my signature in presence of two witnesses.

STEPHEN M. HAMBLIN.
